UNITED STATES PATENT OFFICE.

CHARLES H. SHERWOOD, OF UTICA, ASSIGNOR OF ONE-HALF TO HENRY C. LYMAN, OF SHERBURNE, NEW YORK.

RAILWAY BLOCK-SIGNAL.

SPECIFICATION forming part of Letters Patent No. 530,311, dated December 4, 1894.

Application filed August 8, 1894. Serial No. 519,724. (No model.)

To all whom it may concern:

Be it known that I, CHARLES H. SHERWOOD, of Utica, in the county of Oneida, in the State of New York, have invented new and useful 5 Improvements in Railway Block-Signals, of which the following, taken in connection with the accompanying drawings, is a full, clear, and exact description.

This invention relates to the class of semaphores which are operated by the force of air pumped into a cylinder the piston of which is connected by a rod to the semaphore.

The object of my present invention is to operate said semaphore automatically by the passing trains; and to that end the invention consists in the combination with a series of semaphores dividing the road into blocks, of track-instruments operated by the passing trains, air-pumps operated by said instruments and generating pneumatic pressure, relief valves operated by the track-instruments, cylinders with pistons at the respective semaphores to actuate the same, a pipe extending from the pump at each track-instrument to the semaphore-actuating cylinders at one end of the block, and a pipe leading from the relief-valve at said track-instrument to the semaphore-actuating cylinder at the opposite end of the block; and the invention also consists in a novel construction of the track-instrument and its connection with the air-pump and air-relief valve, all as hereinafter more fully described and specifically set forth in the claims.

35 In the annexed drawings Figure 1 is a plan view of a section of railway supplied with a block-signal system and embodying my improvements. Fig. 2 is an enlarged side view of one of the track-instruments with the 40 pump and valve actuated thereby. Fig. 3 is an outer end view of the same. Fig. 4 is a transverse section on line —4—4— in Fig. 2 viewed in the direction of the arrow thereat. Fig. 5 is a vertical transverse section of the 45 air-pump and pipes connected thereto. Fig. 6 is a vertical transverse section of the connection of the piston-rod of the pump with its revoluble base, and Fig. 7 is a front view of the semaphore and its connection with the 50 track-instrument.

Similar letters of reference indicate corresponding parts.

—F—denotes the railway track and —A— 55 A—A—the semaphores. Each of these semaphores consists of the usual arm —A— which is pivoted to the upper part of a pole or tall post —B— so as to allow the arm to swing toward the track in the usual manner, and as 60 illustrated in Fig. 7 of the drawings. To said pole or post is fastened in an upright position the air-cylinder —D— which is provided with a piston as indicated by dotted lines in said figure. The piston-rod passes through the bottom of the cylinder and is connected by a rod —a— to one end of a lever —c— pivoted to the post. Near the opposite side of the pivot the lever is connected by a rod —c'— to the short rearwardly extending arm —A'— of the semaphore. A weight —C— 65 adjustably connected to the same arm of the lever to which the rod —c'— is connected, serves to depress said arm of the lever and thereby automatically swing the semaphore —A— into its outwardly extending position by which it indicates danger. The semaphore is thrown into a suspended position to 70 indicate safety by means of air forced into the cylinder —D— through the top thereof. This latter effect I attain automatically by 75 my present invention, which I will now describe to enable others skilled in the art to which it pertains to make and use the same.

At or near each of the described semaphores I place a track-instrument —d— consisting of a horizontal shaft —g— disposed 85 at right angles to the outside of the track-rail —F— and journaled to bearings secured to a sill —T— and terminated at one end with a crank —g'— contiguous to the outside 90 of the track-rail as shown in Fig. 2 of the drawings. Said crank is held normally in an upright position so as to project above the plane of the track and be turned by the wheels of the cars or engine traveling over said crank. The crank is held in said position by weight 95 of the pump-piston —G— and the following devices connected therewith: To the lower end of the piston rod is connected a horizontal annular plate —G'— by which it rides upon a two-armed lever —p— attached to the 100

outer end of the shaft —g— and extending at right angles from opposite sides thereof and normally in a horizontal position as shown in Fig. 3 of the drawings. A spiral 5 spring —S— interposed between the top of the plate —G'— and bottom of the pump-cylinder assists in forcing the said plate with the pump-piston downward.

The repeated depressions of the crank 10 —g'— by the wheels of the cars or engine passing over it, rocks the shaft —g— and causes one of the arms of the lever —p— to repeatedly push up the pump-piston by the bearing of said arm on the annular plate 15 —G'— as indicated by dotted lines in Fig. 3 of the drawings.

To obviate friction I pivot to the ends of the lever —p— rollers —p'— by which it bears on the under side of the plate —G'—, 20 and to relieve said rollers from concussion in the descent of the said plate, I attach to the top of the lever —p— cushions —S'— of rubber or other suitable material.

In order to equalize the wear on the under- 25 side of the plate —G'—, I pivot the same to the piston rod as illustrated in Fig. 6 of the drawings.

The air inlet and outlet nozzle —N— is attached to the top of the pump-cylinder, and 30 in order to guard against back pressure of air in the bottom of the cylinder, I provide said bottom with ventiducts —s— as shown in Fig. 5 of the drawings.

To the nozzle —N— is attached a T-joint 35 of a pipe, and to opposite ends of the horizontal portion of said T are connected respectively, the air-inlet —O— and air-discharge pipe —O'— each of which is provided with a suitable check-valve —k—. The discharge pipe —O'— is extended to and communicates with the top of the interior of the cylinder —D— of the semaphore at the rear end of the block of the road. Hence the train of 40 cars in leaving a block of road sets the semaphore at the rear end of the block in a position to indicate safety.

The direction in which the trains travel is indicated by an arrow in the center of the track in Fig. 1 of the drawings, said arrow 45 also indicating the position of the train and the semaphores are shown in their resultant positions.

In order to cause the engine or train of cars to automatically signal danger over the block 50 which said engine or train is entering, I employ the relief-valve —f— which by a pipe —f'— communicates with the top of the interior of the cylinder —D— of the adjacent semaphore —A—, said valve being operated 55 to relieve the cylinder from air by means of an arm —t— attached to the shaft —g— and having its free end over the top of the valve-stem —t'— so as to depress the same when said shaft is rocked by the car-wheels traveling over the track-instrument —d—. The depression of the valve-stem allows the air to escape from the cylinder —D—. The piston

thereof is thus relieved from air pressure and allowed to be forced up by the weighted lever —c— which latter at the same time draws 70 down the rod —c'— and thereby swings the semaphore-arm —A— outward into a horizontal position which indicates danger. The valve —f— is held normally in its closed position by means of a spiral spring —l'— 75 mounted on valve-cage and embracing the valve-stem —t'— and pressing with its upper end against a pin or projection on the stem.

—l— represents an air-supply pipe attached to the inlet —O— of the pump-cylinder, and 80 —m— denotes an air-escape pipe attached to the valve-cage —f—. Both of these pipes I extend to a suitable elevation above the ground and terminate them with short downward deflection to prevent them from becoming choked by snow.

What I claim as my invention is—

1. An automatic pneumatic railway signal system comprising a series of semaphores dividing the road into blocks, track-instruments 90 operated by the passing trains, air-pumps operated by said instruments and generating pneumatic pressure, relief-valves operated by the track-instruments, cylinders with pistons at the respective semaphores to actuate 95 the same, a pipe extending from the pump at each track-instrument to the semaphore-actuating cylinders at one end of the block and a pipe leading from the relief-valve at said track-instrument to the semaphore-actuating 100 cylinder at the opposite end of the block as set forth.

2. In combination with the horizontal shaft —g— provided with the crank —g'— to be operated by the passing engine or cars, an 105 air-pump and a valve controlling the flow of compressed air, and a crank and lever both attached to the shaft —g— and operating respectively the aforesaid pump and valve as set forth.

3. In combination with the shaft —g— provided with the crank —g'—, the arm —t—, and two-armed lever —p— attached to said shaft the pump —P— and plate —G'— attached to the lower end of the piston-rod and 115 riding on the lever —p—, and the valve —f— disposed with its valve-stem opposite the arm —t— as set forth and shown.

4. In combination with the shaft —g— provided with the crank —g'—, the arm —t— 120 and two-armed lever —p— attached to said shaft the pump —P—, the plate —G'—, attached to the piston-rod and riding on the lever —p—, the springs —S— interposed between said plate and pump-cylinder, and the 125 valve —f— having its valve-stem opposite the arm —t— as set forth.

5. In combination with the shaft —g— provided with the crank —g'—, the two-armed lever —p— attached to said shaft, the pump 130 —P— and the plate —G'— pivoted to the piston-rod and riding on the aforesaid lever as set forth.

6. In combination with the shaft —g— pro-

vided with the crank —*g'*—, the two-armed lever —*p*— attached to said shaft, rollers —*p'*—*n'*— pivoted to said lever, the pump —*P*— over the lever, and the plate —*G'*— connected to the piston-rod and extending over the aforesaid rollers as set forth.

7. In combination with the shaft —*g*— provided with the crank —*g'*—, the two-armed lever attached to said shaft, cushions —*S'*— secured to the top of said lever, rollers —*p'*— pivoted to the ends of the lever, the

pump —*P*— and the annular plate —*g'*— attached to the piston-rod and riding normally on the cushions and extending over the rollers as set forth and shown.

In testimony whereof I have hereunto signed my name this 24th day of July, 1894.

CHARLES H. SHERWOOD. [L. s.]
